(57) **CLAIM**

The ornamental design for a novelty hose, as shown and described.

DESCRIPTION

FIG. 1 is a front elevational view of the novelty hose of the present invention;

FIG. 2 is a rear elevational view of the novelty hose of FIG. 1;

FIG. 3 is a right side elevational view of the novelty hose of FIG. 1, the left view being a mirror image thereof;

FIG. 4 is a top plan view of the novelty hose of FIG. 1;

FIG. 5 is a bottom plan view of the novelty hose of FIG. 1; and,

FIG. 6 is a front, left side perspective view in an alternate position (worn and legs crossed) of the novelty hose of FIG. 1.

The broken lines showing of words in FIGS. 1 and 6, and the lady and bench in FIG. 6 are for illustrative purposes only and form no part of the claimed design.
